FILING MACHINE

Lawrence J. Tansey, Detroit, and John B. Hoy,
Ferndale, Mich., assignors, by mesne assignments,
to Mechanical Finishing Co., a corporation of Michigan

Application October 18, 1947, Serial No. 780,632

8 Claims. (Cl. 29—76)

1

This invention relates to filing devices, and more particularly to a device attachable to an air-operated motor which reciprocates the file at high speed.

The pneumatically operated motor embodies a cylinder having a pair of pistons therein suitably connected through the valve means to an air supply conduit for reciprocating a pair of plates toward and away from each other. A block of metal is attached to each of the plates, the one having means for supporting the file and the other being of a weight substantially equal to the file and its supporting block so as to have each plate of the motor operate equal weights of material.

The file supporting device embodies a rod having means at each of its ends for supporting a clamping bracket which engages slots in the end of the file for supporting it on the device while retaining it against lateral displacement. This may be accomplished by shaping the slots in the form of an arc which may be convex or concave and employing clamping brackets provided with a flange of arcuate shape which mates with the arc of the slots when disposed therein for preventing lateral displacement.

In another form of the invention, the sides of the clamping bracket may extend inwardly to project over the side edges of the file ends to prevent lateral displacement. In still another form of the invention, angular slots may be provided at the corners of the file and the bracket formed to project into the corner slots and thereby prevent lateral displacement.

Accordingly, the main objects of the invention are: to provide a filing attachment for an air motor embodying parts which reciprocate toward and away from each other which are of equal weights; to provide a filing device having a fluid motor with driven plates in reciprocation toward and away from each other, to one of which plates the file is supported and on the other of which an element is secured of equal weight to the movable file assembly; to provide a filing device embodying a block secured to one reciprocating plate of a fluid motor having a rod extending therethrough containing file supporting brackets at each of its ends, with the rod extending through an aperture in a second block which is supported on a second reciprocating plate of the motor and which is of a weight equal to the first block and movable file assembly; and, in general, to provide a filing attachment for a fluid motor which is simple in construction, positive of operation and economical of manufacture.

Other objects and features of novelty of the

2

invention will be specifically pointed out or will become apparent when referring, for a better understanding of the invention, to the following description, taken in conjunction with the accompanying drawing, wherein:

Fig. 1 is a sectional view of a fluid motor having a filing device attached thereto which embodies features of this invention;

Fig. 2 is an enlarged sectional view of one end of the device illustrated in Fig. 1, taken on the line 2—2 thereof;

Fig. 3 is a broken sectional view of a portion of the device illustrated in Fig. 2, showing a modified form thereof;

Fig. 4 is a sectional view of the structure illustrated in Fig. 3, taken on the line 4—4 thereof;

Fig. 5 is a view of structure, similar to that illustrated in Fig. 3, showing a further form which the invention may assume, and

Fig. 6 is a sectional view of the structure illustrated in Fig. 5, taken on the line 6—6 thereof.

In the figures, the fluid operated motor 10 may be of any construction so long as it provides reciprocating movement to a pair of work plates 11 and 12 toward and away from each other.

The device herein illustrated is described in United States Patents 1,524,902, 1,590,353 and 1,677,112 and is therefore not shown herein in detail. The fluid motor herein illustrated comprises a housing 13 containing a cylinder 14 in

which a pair of pistons 15 and 16 is mounted to reciprocate toward and away from each other. Air is introduced through a line 17 to an end cap 18 of the housing 13 through a valve 19 to a passageway 21 leading into a valve chamber 22.

The valve 19 is unseated by a rod 23 actuated by a palm lever 24 on the top of the motor.

A valve 25 in the chamber 22 is actuated by a rod 26 carried by a plate 27 which is oscillated by pins 28 extending from plates 29 and 30 secured to the work plates 11 and 12. The plates 11 and 12 are connected by shafts 31 to the respective pistons 15 and 16, and as the pistons reciprocate toward and from each other, the work plates 11 and 12 also move toward and from each other. This movement reciprocates the rod 26 to operate the valve 25 for introducing the air on opposite sides of the piston to produce the reciprocating movement thereof and the exhausting of the air through the passageway 32.

Ahead of the supply line 17, and not herein illustrated, a moisture trap is preferably provided, the air from which passes through a pressure regulator and through an automatic air lubricator for lubricating the cylinder, pistons and other working parts of the fluid motor. Some of this

55

lubricant is exhausted with the air from the passageway 32 and will be referred to hereinafter.

The filing device attachable to the work plates 11 and 12 embodies a rectangular block 33 having a slot 34 therein for receiving the work plate 11 to which it is secured by suitable means, such as by screws. A rod 35 is threaded through the block 33 and is secured in position thereon by a lock nut 36. The left-hand end of the rod 35, as viewed in the figure, has a nut 37 thereon which also clamps the block 33 and engages a bracket 38 which is clamped on the rod by a nut 39 which is tightened against a reinforcing plate 41. The right-hand end of the rod 35 has a similar bracket 42 secured in position by a pair of nuts 43 and 44 which are tightened against the bracket and a reinforcing plate 45. A file 46 is supported by the brackets 38 and 45 for reciprocation with the block and the work plate 11.

The work plate 12 has a block 47 secured thereto by screws 48 and is provided with an aperture 49 through which the rod 35 extends. The block 47 has a pair of sleeve bearings 51 at each end, with an oil wick 52 disposed therebetween and about the rod. An O-ring 53 seals the ends of the block to the rod 35 when squeezed by packing nuts 54 threaded in the opposite ends of the aperture 49. An oil passageway 55 extends from the top surface of the block 47 into the aperture 49, the upper end being chamfered at 56 to form an enlarged opening for receiving the lubricant which may drain from the exhaust passageway 32, as mentioned hereinabove. The block 47 is made of brass or other heavy material so that its weight will equal the weight of the block 33, the rod 35, the supporting brackets 38 and 42 and the file 46. The weight of the elements supported by the plates 11 and 12 being equal, any vibrations which otherwise might be set up in the device during operation are eliminated.

Referring to Figs. 1 and 2, the brackets 38 and 42 have a projecting flange 57 provided with an arcuate end portion 58 which engages the arcuate edge 59 of a slot 61 provided in both ends of the file interjacent the top and bottom surfaces. The brackets are drawn toward each other to force the flanges 57 into the slots 61 in the file with the arcuate surfaces in engagement so that the file will be secured in position against movement laterally from the brackets. By having the slot placed midway between the top and bottom surfaces, after one side of the file becomes dull, it is only necessary to adjust one bracket to reverse the file and present the other working face thereof for further operations.

Referring to Figs. 3 and 4, a further form of the invention is illustrated, that wherein brackets 62 are provided in place of the brackets 38 and 42, having an inwardly projecting lip 63 and side flanges 64. The file has a slot 65 across the end in which the lip 63 projects for holding the file while the flanges 64 prevent it from shifting laterally of the device.

In Fig. 5 a further form of bracket 66 is illustrated, that having projecting ears 67 which project in slots 68 provided at each corner of the file. The ears 67 support the file and prevent it from being shifted laterally.

In operating the device, the air pressure is regulated to produce the reciprocation of the pistons and file at a speed conforming to the amount of pressure the operator is to apply to the device. The device is controlled by the operator through the manipulation of the palm lever 24, and when in full operation the file reciprocates at a rate of three thousand to four thousand times a minute.

Each reciprocation is opposed by the reciprocation of the block 47 which moves in the opposite direction to the file. The reciprocating parts being of the same weight, the vibrations which would otherwise be set up are eliminated.

What is claimed is:

1. A filing machine including a motor having two oppositely reciprocating work plates, a block secured to each of said plates, a rod attached to and supported rigidly by one block and slidably extending through an aperture in the other block, brackets supported on the ends of the rod for relative adjustment toward and away from each other, and a file supported by the brackets, the weight of the block through which the rod extends being substantially equal to the weight of the other block, the brackets and the file.
- 10 2. A filing machine including a motor having two oppositely reciprocating work plates, a block secured to each of said plates, a rod attached to and supported by one block and slidably extending through an aperture in the other block, brackets supported on the ends of the rod for relative adjustment toward and away from each other, and a file supported by the brackets, the weight of the block through which the rod extends being substantially equal to the weight of the other block, the brackets and the file.
- 15 3. In a device attachable to a motor having two oppositely reciprocating plates, a pair of blocks secured to said plates, a rod secured in fixed relation to one block and slidably extending through an aperture in the other block, brackets adjustably secured on the ends of the rod for movement toward and away from each other and having aligned flanges projecting toward each other for supporting a file.
- 20 4. In a device attachable to a motor having reciprocating plates, a pair of blocks secured to said plates, a rod secured in fixed relation to one block and slidably extending through an aperture in the other block, brackets adjustably secured on the ends of the rod for movement toward and away from each other and having aligned flanges projecting toward each other for supporting a file.
- 25 5. In a device attachable to a motor having reciprocating plates, a pair of blocks secured to said plates, a rod secured in fixed relation to one block and slidably extending through an aperture in the other block, brackets adjustably secured on the ends of the rod for movement toward and away from each other and having aligned flanges projecting toward each other for supporting a file.
- 30 6. In a device attachable to a motor having reciprocating plates, a pair of blocks secured to said plates, a rod secured in fixed relation to one block and slidably extending through an aperture in the other block, brackets adjustably secured on the ends of the rod for movement toward and away from each other and having aligned flanges projecting toward each other for supporting a file.
- 35 7. In a device attachable to a motor having reciprocating plates, a pair of blocks secured to said plates, a rod secured in fixed relation to one block and slidably extending through an aperture in the other block, brackets adjustably secured on the ends of the rod for movement toward and away from each other and having aligned flanges projecting toward each other for supporting a file.
- 40 8. In a device attachable to a motor having reciprocating plates, a pair of blocks secured to said plates, a rod secured in fixed relation to one block and slidably extending through an aperture in the other block, brackets adjustably secured on the ends of the rod for movement toward and away from each other and having aligned flanges projecting toward each other for supporting a file.
- 45 9. In a device attachable to a motor having reciprocating plates, a pair of blocks secured to said plates, a rod secured in fixed relation to one block and slidably extending through an aperture in the other block, brackets adjustably secured on the ends of the rod for movement toward and away from each other and having aligned flanges projecting toward each other for supporting a file.
- 50 10. In a device attachable to a motor having reciprocating plates, a pair of blocks secured to said plates, a rod secured in fixed relation to one block and slidably extending through an aperture in the other block, brackets adjustably secured on the ends of the rod for movement toward and away from each other and having aligned flanges projecting toward each other for supporting a file.
- 55 11. In a device attachable to a motor having reciprocating plates, a pair of blocks secured to said plates, a rod secured in fixed relation to one block and slidably extending through an aperture in the other block, brackets adjustably secured on the ends of the rod for movement toward and away from each other and having aligned flanges projecting toward each other for supporting a file.
- 60 12. In a device attachable to a motor having reciprocating plates, a pair of blocks secured to said plates, a rod secured in fixed relation to one block and slidably extending through an aperture in the other block, brackets adjustably secured on the ends of the rod for movement toward and away from each other and having aligned flanges projecting toward each other for supporting a file.
- 65 13. In a device attachable to a motor having reciprocating plates, a pair of blocks secured to said plates, a rod secured in fixed relation to one block and slidably extending through an aperture in the other block, brackets adjustably secured on the ends of the rod for movement toward and away from each other and having aligned flanges projecting toward each other for supporting a file.
- 70 14. In a tool, a motor, two work plates driven by said motor for producing counter-reciprocating movement, a reciprocable block driven by one plate, a rod rigidly secured to and extending from said block, means on said rod for supporting a work producing element, and a second reciprocable block driven by said other plate having an aperture through which said rod extends for re-

ciprocation in a direction opposite to said second block.

7. In a file attachment for a motor having two work plates for producing counter-reciprocating movement, a reciprocable block driven by one plate, a rod extending from said block, means on said rod for supporting the file, a second reciprocable block driven by said other plate and having an aperture through which said rod extends, a bearing provided on each end of said second block in engagement with said rod, and a wick disposed about said rod between said bearings, said second block having a passageway for a lubricant extending into the aperture at the portion containing said wick.

8. In a file attachment for a motor having two work plates for producing counter-reciprocating movement, a reciprocable block driven by one plate, a rod extending from said block, means on said rod for supporting the file, a second reciprocable block driven by said other plate and having an aperture through which said rod extends, a bearing provided on each end of said second block in engagement with said rod, a wick disposed about said rod between said bearings, said second block having a passageway for a lubricant extending into the aperture at the portion containing said wick, sealing elements adjacent to said bearings, and threaded sleeves on the ends of the aperture of said second block for applying pressure to said sealing elements.
